UNITED STATES PATENT OFFICE.

ROBERT M. GLOR, ALVIN J. GLOR, AND WILLIAM P. WEST, OF ATTICA,
NEW YORK.

CARRIER FOR ENSILAGE AND OTHER THINGS.

No. 855,398.

Specification of Letters Patent.

Patented May 28, 1907.

Application filed January 21, 1907. Serial No. 363,274.

To all whom it may concern:

Be it known that we, ROBERT M. GLOR,
ALVIN J. GLOR, and WILLIAM P. WEST, all of
Attica, Wyoming county, New York, have
invented a new and useful Improvement in
Carriers for Ensilage and other Things, of
which the following is a full, clear, and exact
description.

Our invention relates to improvements in
that class of carriers which are used in con-
nection with an overhead supporting track,
and which convey ensilage, coal, fertilizer,
or any loose materials from one point to an-
other.

The object of our invention is to produce a
simple device of this character which is
cheap and strong, and which can be used to
great advantage chiefly because it can be
easily loaded and unloaded.

In furtherance of this idea our invention
has for its object more particularly the ar-
rangement of one of the end doors or gates,
and means for readily dropping and opening
or locking the gate.

With these ends in view our invention con-
sists of certain features of construction and
combinations of parts which will be herein-
after described and claimed.

Reference is to be had to the accompany-
ing drawings forming a part of this specifica-
tion, in which similar figures and letters of
reference indicate corresponding parts in all
the views.

Figure 1 is a side elevation of the device
embodying our invention. Fig. 2 is an end
view of the same. Fig. 3 is a sectional plan
on the line 3.3 of Fig. 1 of the carrier. Fig. 4
is a side elevation of a modified form and pre-
ferred form of carrier. Fig. 5 is an end view
of the structure shown in Fig. 4, and Fig. 6 is
a sectional plan on the line 6.6 of Fig. 5.

The carrier consists in the main of a box-
like structure 10 which is open at the top,
and which is formed of sheet metal or other
suitable materials, which is attached to the
bails 11 which extend upward from the car-
rier ends. These bails are formed by ex-
tending up the corner posts of the carrier and
connecting them together across the top. If
desired the two bails can be braced by a rod
12 which connects them. The carrier is in-
tended to run on a track 14, and to this end
the bails 11 have at the top trolleys 13, each
having a stirrup 14^a with the trucks 15 piv-

oted therein, and the trucks run on the track. 55
The stirrups connect by the tie-plate 16 and
this is stiffened by the spring braces 17 of
bow construction, these being placed at right
angles to each other, and the ends of one are
secured to the tie-plate so that the bend rests 60
against the bail top while the ends of the
other are secured to the bail, and the middle
portion rests against the stirrup bottom as
shown in Fig. 2.

In Figs. 1 to 3 I have shown an end gate 18, 65
which is locked by the bolts 19, these being
attached above and below the pivot to the
swiveling handle 20, and the ends of the
bolts engage ears 21 on the sides of the car-
rier, and thus by turning the handle the bolts 70
can be locked or released. At the lower end
of the gate 18 has eyes 22, which run on the
track 23 this extending around the carrier
end and running along below the bottom par-
allel therewith, as shown clearly in Fig. 1. 75
Thus by dropping the gate it can be pushed
back on the tracks 23 and held so as to be out
of the way, and by pulling it forward or
swinging it up, it can be instantly locked.

In Figs. 4 to 6 I have shown a preferred 80
construction, and here the trolleys 13^a are
modified, and the tie-plate 16 is reinforced
by a strap 16^a laid parallel with it. In both
forms of structure the corner posts or bails
are formed of angle iron, but in the form 85
shown in Figs. 4 to 6, the end gate 18 is stiff-
ened by a rib of angle iron 18^a, which runs
preferably all the way around it, and the
form of the locking bolts 19 is changed.
These are attached to the lever 20^a which is 90
centrally pivoted and has a handle 24. The
bolts extend through the angle iron 18^a, are
bent around the sides of the carrier 10, as
shown at 19^a and terminate in hooks 19^b
which enter slots 25 in the sides of the car- 95
rier. Another improvement in the structure
shown in the figure referred to, is that the de-
vice has a guard bail 26 at the bottom, ex-
tending entirely across the carrier, upon
which the gate 18 can be dropped, and the
bail 26 prevents the gate from dropping too 100
low and holds it always in the right position
for easy handling.

From the foregoing description it will be
seen that the device is very simple, very 105
strong, and that it can be readily loaded and
unloaded by reason of the arrangement of
the end gate.

Having thus fully described our invention, we claim as new and desire to secure by Letters Patent:—

1. A structure such as described, comprising a box having upwardly extending bails at the ends, and provided with an end gate, a hinge connection between the lower part of the gate and the box, and means for permitting the hinged part to slide beneath and parallel with the box.

2. A device of the kind described, comprising a box open at the top and provided with an end gate, the corner posts of the box being formed of angle irons which are projected upward and formed into the supporting bails.

3. In a carrier, the combination with the box, of the outwardly and downwardly swinging end gate, a locking device to fasten the upper part of the gate, and guiding devices slidably supporting the lower end of the

gate, said guiding devices extending beneath the box.

4. In a carrier, the combination with the box, of the outwardly and downwardly swinging end gate arranged to slide beneath the box when open, and a depending bail on the box to support the gate.

5. The combination with the box, of the outwardly and downwardly swinging end gate, the track extending from the front part of the box, beneath it and along the bottom, and the sliding and supporting connections between the lower part of the gate and the tracks.

ROBERT M. GLOR.
